US00D537449S

(12) **United States Design Patent** (10) **Patent No.:** **US D537,449 S**
Hoefnagels et al. (45) **Date of Patent:** ** *Feb. 27, 2007

(54) **USER INTERFACE FOR A PORTION OF A DISPLAY SCREEN**

(75) Inventors: **Stephan Hoefnagels**, Seattle, WA (US); **Olivier d'Hose**, Seattle, WA (US); **James H. Hong**, Seattle, WA (US); **Michael James Hone**, Seattle, WA (US)

(73) Assignee: **Microsoft Corporation**, Redmond, WA (US)

(*) Notice: This patent is subject to a terminal disclaimer.

(**) Term: **14 Years**

(21) Appl. No.: **29/246,093**

(22) Filed: **Feb. 7, 2006**

(51) **LOC (8) Cl.** **14-04**

(52) **U.S. Cl.** **D14/485**

(58) **Field of Classification Search** 715/500.1, 715/501.1, 526, 530-31, 539, 708, 711, 717, 715/723, 726, 733, 738, 753, 762, 763-4, 715/767-69, 778-82, 788, 790, 793-94, 715/797-8, 802-10, 835-40, 848-856, 862-63, 715/976, 978; 345/757, 782, 848, 852, 850, 345/809, 837, 798, 752, 163, 156, 537, 474, 345/836, 419, 649, 656, 659, 426, 427, 582, 345/428, 440, 660, 634, 902, 418, 629; D14/485-94; D18/24-33; D20/40, 11; D19/6; D21/324-33; 434/43, 38; 382/305; 400/76; 710/5, 73; 707/102, 707/2; 463/32, 16; 717/170; 705/26, 27

(57) **CLAIM**

The ornamental design for a user interface for a portion of a display screen, as shown and described.

DESCRIPTION

The FIGURE is a front view of a user interface for a portion of a display screen showing our new design.

The broken line showing of various regions and the unshaded areas there within form no part of the claimed design. The broken line showing of the display screen is for illustrative purposes only and forms no part of the claimed design.
